Frank Hohmann

By Charles Turner Brown, Atty.

UNITED STATES PATENT OFFICE.

FRANK HOHMANN, OF CHICAGO, ILLINOIS.

ELASTIC SUPPORT FOR TROUSERS.

Application filed December 13, 1922. Serial No. 606,726.

To all whom it may concern:

Be it known that I, FRANK HOHMANN, a citizen of the United States, and a resident of Chicago, in the county of Cook and State 5 of Illinois, have invented certain new and useful Improvements in an Elastic Support for Trousers, of which the following, when taken in connection with the drawing accompanying and forming a part hereof, is 10 a specification.

This invention relates to belt supports for trousers; and among the objects of the invention is to obtain an elastic belt support; that is, a support which comprises an ordinary belt and in addition thereto provides 15 means whereby desired elasticity is obtained, to permit free motion of the body of the person wearing the same. An additional object is to obtain an elastic support for 20 trousers which is attachable to buttons placed on the inside of the waist of the trousers; which permits the device embodying the invention, including the belt, to be placed on the inside of the trousers, which 25 is readily adjustable to fit the location of the buttons on the trousers; which is economically made, is durable; and the attachment and operation whereof is readily understood and easily manipulated.

29 In the drawings referred to Fig. 1 is a perspective of an elastic support embodying the invention.

Fig. 2 is a vertical section through the belt forming a member of the device and 35 through one of the elastic members thereon, together with a section of the upper portion of trousers attached thereto,

Fig. 3 is an elevation of one of the elastic members of the device, with a side elevation 40 of a portion of the belt on which it is mounted, showing a button of the trousers engaged by said elastic member.

Fig. 4 is an elevation of a metal support 45 forming an element of the elastic support illustrated in Fig. 3, with a loop element which is illustrated as formed up of wire and attached to said support.

Fig. 5 is a perspective of the loop element 50 which is illustrated in Fig. 4; and

Fig. 6 is a perspective of the metal support which is illustrated in Fig. 4.

Figs. 3, 4, 5 and 6 are on an enlarged scale.

A reference character applied to designate a given part indicates said part

throughout the several figures of the drawing wherever the same appears.

1 represents a belt of the ordinary construction, having the buckle members 1^a adjustably attached to the ends thereof. 1^a 60 represents a metal member forming an element of the elastic support, which is provided with the apertures 1^c, 1^c. 1^d a member which forms an element of the elastic support, and is secured to the member 1^a. 65 Member 1^d is illustrated as bent up of wire to obtain bar 1ⁱ, over which the elastic member 1^c extends. Member 1^d is bent up to obtain the ends 1^f, 1^f, and the bends 1^h, 1^h. In assembling the members 1^a and 1^d, the 70 ends 1^f, 1^f, and bends 1^h, 1^h, extend through the apertures 1^c, 1^c, with said bends resting in said apertures, as is well illustrated in Fig. 4. 2^a represents a covering of textile material which extends over the member 1^a, 75 and below the lower end thereof, and over the greater part of member 1^d, but not over the bar 1ⁱ, leaving said bar exposed for the elastic member 1^c to extend thereover. The lower end of the elastic member 1^c is secured 80 to the textile cover 2^a, as by stitching 1ⁱ, Fig. 2. 1^b represents a triangular shaped wire member which is attached to the upper end of the elastic member 1^c, and is adapted 85 to be attached to button 3^a. The button is attached to the inside of the trousers band as by stitching 3^b, Figs. 2 and 3. 2^b represents a portion of a pair of trousers.

To obtain the loop through which the belt 1 is extended I carry the textile material 90 forming the covering 2^a below the lower end of metal member 1^a and loop it upwards, attaching it, at its end to said covering 2^a, as by stitching at 2, Fig. 2.

To attach the trousers to the triangular 95 loop 1^b the button 3^a is passed through said loop, into the position illustrated in Figs. 2 and 3.

Before engaging the triangular member 1^b with a button 3^a, the elastic support is 100 moved along the belt 1 into proper relative position with said button, and when said engagement is made the elastic member 1^c is drawn over the bar 1ⁱ of member 1^d; and by the movement of the body of the person 105 wearing device said members 1^b are drawn down by the lengthening of said elastic members 1^c, correspondingly with said movement of the body.

By the foregoing described construction 110

I obtain an elastic support for trousers, the several members of which are adjustable on the belt on which they are mounted, and the belt is on the inside of the waist band of the trousers, and is not exposed to view.

I claim:

1. In an elastic support for trousers, a plurality of metal standards, bars offset from said standards at the upper ends thereof, coverings of textile material on said standards, said coverings respectively extended below the corresponding metal standard and the ends thereof attached to said coverings midway of said standards to form loops, triangular metal members respectively adapted to engage with a trousers button, and elastic members respectively secured at the lower end thereof to a corresponding covering and at the upper end extending over said bar corresponding therewith and attached to a corresponding one of said triangular members, in combination with a belt arranged to extend through said

loops, to movably mount said elastic supports thereon.

2. An elastic support for trousers comprising a metal standard, a bar offset from said standard at the upper end thereof, a covering of textile material on said standard, said covering extended beyond said standard and the end thereof attached to said covering midway of said standard to form a loop, a triangular metal member adapted to engage with a trousers button and an elastic member secured at the lower end thereof to said covering and at the upper end extending over said bar and attached to said triangular member, in combination with a belt arranged to extend through said loop to movably mount said elastic support thereon.

FRANK HOHMANN.
